SIPHON

Lawrence T. Ward, New York, N. Y., assignor to
Sparklets Limited, London, England, a corpo-
ration of Great Britain

Application August 20, 1936, Serial No. 97,006

6 Claims. (Cl. 215—4)

My invention relates to siphons and particularly to rechargeable soda siphons. These siphons as heretofore made usually consist of a glass bottle or vase that is reenforced by a woven 5 wire jacket or other metallic covering as in the well-known "Sparklets" siphon. Each siphon has a removable siphon tube that extends nearly to the bottom and is held in place at the top by a removable head. This head has a valve controlled discharge nozzle through which carbonated water from the siphon tube is discharged, and a charging head which has a cooperating bulb holder into which the carbon dioxide capsule is inserted for carbonating the liquid in the siphon. The glass vase forming the body of the siphon has a colored filling line marked on it which indicates the maximum level to which the siphon is to be filled with liquid before carbonating in order to produce the best carbonating of 10 the liquid and the best safe working pressure. It sometimes happens through carelessness or inexperience that the person preparing the siphon for use fills it above the filling line. The result is that the increased volume of water is not 15 properly carbonated and too high pressure is produced in the siphon. Also the glass vases, even though covered with metal reenforcement, are subject to breakage when dropped or struck sharply against a metal object or fixture.

30 Among the objects of the present invention, therefore, is to provide a filling or measuring tube within the siphon so that it can not be filled above a predetermined level.

Another object is to provide means whereby 35 the measuring tube may be quickly and easily removed for cleaning the inside of the siphon.

Another object is to provide a safety device or vent so that the siphon can not be charged if the filling tube is omitted.

40 Still another object of the invention is to provide an all metal siphon, thereby doing away with the glass vase.

Yet another object is to provide a metal siphon made in two parts detachably connected together, the upper part including the siphon head, siphon tube and measuring tube being removable 45 as a unit.

Another object is to provide a two part metal siphon with the measuring tube formed integral 50 with or fixedly secured to the top removable section.

Another object is to provide a siphon having removable interchangeable siphon and shaker heads, whereby the body may be used either as a 55 siphon or cocktail shaker.

The above and other objects and advantages of the invention are attained by the embodiments thereof that I have illustrated in the accompanying drawings wherein:

Fig. 1 shows a metal siphon having a removable measuring tube.

Fig. 2 shows a similar metal siphon with the body made in two parts.

Fig. 3 illustrates how the siphon body may be 5 used with an interchangeable head as a cocktail shaker.

Fig. 4 is an enlarged view, partly in section, of the siphon shown in Fig. 1.

Fig. 5 shows how the measuring tube may be 10 removed.

Fig. 6 shows how the gas may escape through the safety port if the measuring tube or its sealing washer is omitted.

Fig. 7 is a sectional view of a metal siphon with 15 the filling tube integral with the top section.

Fig. 8 is a sectional view of a siphon having a glass vase with a measuring tube applied thereto.

Referring now to Figs. 1 and 4, the body 16 of the siphon is made of metal and has a bottom 11 that is brazed or soldered in place so that the body 20 is in effect a single piece. The neck 12 is externally screw-threaded at 13 to receive the siphon head 14 which has a nozzle 15 controlled by the valve 16 and lever 17. A charging head 18 opens 25 into an expansion chamber 19 in the siphon head 14 and is adapted to receive either the bulb holder 20 and carbon dioxide bulb 21 for charging the siphon or the closure cap 22 after the siphon has been charged.

The neck 12 has an internal recess providing a seat 23 and is screw-threaded to receive the screw-threaded upper end 24 of the filling and measuring tube 25, which extends down in the siphon to the filling level. The measuring tube 30 is enlarged or has a flange at its upper end the top of which lies substantially flush with the top of the neck and the lower side of which engages a gasket 26 to make a tight joint with the seat 23. The measuring tube 25 is provided with some 35 means, as lugs 27, adapted to be engaged by the wrench 28 or other suitable tool so that it may readily be removed or inserted for any reason, as 40 for cleaning or converting the siphon into a shaker.

The siphon tube 28 may be either glass or metal 45 and extends nearly to the bottom of the siphon. It has a flanged head 30 at its upper end which engages the rubber gasket 31 and when the head 35 50 55 60 65 70 75 80 85 90 95 100 105 110 115 120 125 130 135 140 145 150 155 160 165 170 175 180 185 siphon contains just the right quantity of liquid for proper carbonating when filled up to the end of the tube. The siphon tube, gasket and head are now replaced and the head screwed down tightly. The liquid is now ready to be carbonated and the size of the chamber 32 is such as to insure the proper working pressure within the siphon. In case the operator should be careless or intentionally leave out the measuring tube 25, so that the siphon may be filled above the desired level, I provide a safety port 33 leading from the seat 23 to the outside of the neck, which will be left open by omission of the tube 25 and gasket 24 so that the gas will escape and dangerous pressure can not be built up in the siphon, as best shown in Fig. 6.

In Figs. 2 and 7 I show the siphon body made in top and bottom sections 34, 35, removably secured together by screw-threads 36, 37 and a packing ring 38. The same siphon head 14, siphon tube 29 and gasket 31 are used in these modifications as in Figs. 1 and 4, but the measuring tube 39 may be integral with the top section 34, as shown in Fig. 7, or it may be removable like tube 25. The top section 34 is drawn in to provide a neck 40 (Fig. 7) that is screw-threaded to receive the head 14. While the tube 39 and section 34 are shown integral in Fig. 7, and are so described, they may originally be formed as separate parts and brazed or soldered together to form a single piece, the junction of the neck 40 and tube 39 providing a seat 41 for the gasket 31.

The lower end of the filling tube terminates substantially at the dividing line between the top and bottom sections, but, of course, the two parts may be separated at any other preferred level.

In Fig. 3 I have shown how my improved siphon may be used as a cocktail shaker. The shaker may be made by using the lower section 35 of the siphon shown in Figs. 2 and 7, and replacing the top section 34 with a plain section 34' closed by a removable shaker head 42. The head 42 may be secured to the section 34' in any suitable manner, but generally the section 34' has a screw-threaded neck the same as the neck 40 so that the shaker head 42 and siphon head 14 are interchangeable. The head 42 has a pouring spout closed by a cap 43.

The siphon shown in Figs. 1 and 4 may likewise be used as a shaker. To thus convert the siphon, the head 14, siphon tube 29, and measuring tube 25 are removed and the shaker head 42 screwed on the neck 12 after the siphon body has been filled with the required ingredients. Likewise, both sections 34, 35 of the siphon of Figs. 2 and 7 may be utilized in the shaker if the tube 39 is made removable.

In Fig. 8 I have shown a removable filling tube 44 adapted for use with a siphon having a glass vase or body 45 covered with a woven wire mesh 46 such as the well-known "Sparklets" siphon. At its upper end the tube 44 is flanged as at 47 and is engaged by a rubber sleeve or packing 48 that fits snugly in the neck 49 of the vase 45. A metal neck 50 is secured to the siphon and is screw-threaded to receive the siphon head 14. The filling or measuring tube 44 extends down to the filling line of the siphon and prevents its being filled too full. The tube 44 is easily removed upon removal of the head 14 and siphon tube 29.

Having thus described several forms that my invention may take, it will be apparent to those skilled in this art that it may be embodied in many other forms and modifications, and I claim

as my invention all such that may come within the scope or spirit of my claims.

What I claim is:

1. In a rechargeable siphon, the combination of a siphon body having a neck at its upper end, a recess providing an annular seat formed within said neck, there being a safety port leading from said annular seat through said neck, a measuring tube extending into the siphon and having a flange at its upper end removably secured within said recess, a packing between said annular seat and flange, a siphon tube within said measuring tube, and a siphon head removably secured to said neck and holding said siphon tube in place. 5

2. In a rechargeable siphon, the combination of a siphon body having a neck, a screw-threaded recess formed in said neck and providing an annular seat at the bottom thereof, a removable measuring tube extending a predetermined distance into the siphon with its upper end screwed into said recess and bearing on said annular seat, 20 tool engaging means within said measuring tube for effecting its engagement with and removal from said threaded recess, a siphon tube within said measuring tube, and a siphon head engaging 25 said neck and siphon tube. 15

3. In a device of the class described, a metal siphon body having a neck at its upper end, a measuring tube extending into the siphon and formed integrally with said neck, a siphon head 30 detachably secured to said neck, said siphon body being made in two sections detachably secured together below said neck.

4. In a rechargeable siphon, the combination of a siphon body having an externally screw 35 threaded neck, a screw threaded recess within said neck, a measuring tube having a threaded flange at its upper end secured in said recess and extending into the siphon, the upper face of said flange being flush with the top of said neck, a gasket engaging said flange and neck, a siphon 40 tube extending through said filling tube and having a head at its upper end engaging the top of said gasket, and a siphon head screw threaded on said neck and pressing said gasket into sealing 45 engagement with said neck and flange. 40

5. In a rechargeable siphon, the combination of a siphon body having an externally screw threaded neck, a screw threaded recess within said neck having an annular seat at the bottom thereof, there being a safety port leading from 50 said annular seat through said neck, a packing ring on said seat, a removable measuring tube having a threaded flange at its upper end secured in said recess and bearing on said packing ring, the upper face of said flange being substantially 55 flush with the top of said neck, said measuring tube being provided internally with tool engaging means to effect its removal from and insertion in said recess, a siphon tube extending through said measuring tube, a gasket bearing on 60 the top of said neck and the upper face of said flange, and a siphon head screwed on said neck and forcing said gasket into sealing engagement with said neck and flange. 65

6. In a rechargeable siphon, the combination of a siphon body having a neck, a measuring tube extending through the neck and into the siphon body, a siphon tube within the measuring tube, a siphon head securing said siphon tube in position, said siphon body having a relief passage 70 that is normally closed by said measuring tube but is opened upon removal of the measuring tube. 75
